UNITED STATES PATENT OFFICE.

JOHN J. McDONALD, OF LYNN, MASSACHUSETTS.

ADJUSTABLE FLUE-RECEIVER.

975,703.

Specification of Letters Patent. Patented Nov. 15, 1910.

Application filed February 28, 1910. Serial No. 546,341.

To all whom it may concern:

Be it known that I, JOHN J. McDONALD, a citizen of the United States, residing at Lynn, in the county of Essex and State of Massachusetts, have invented new and useful Improvements in Adjustable Flue- Receivers, of which the following is a specification.

This invention relates to improvements in 10 flue receivers for chimneys of that class in which the chimney extends up through the walls of the building and is provided with a hole to receive the flue of the stove, the adjacent wall being provided with a larger 15 hole through which the flue extends into the hole in the chimney.

The building laws require that a tube shall be fitted into the hole in the chimney to receive the flue and another tube fitted into 20 the adjacent hole in the wall. There is always more or less shrinking and settling of the walls with relation to the chimney, the amount, of course, being greater at the upper story or stories than at the lower story. 25 In practice, the face of the chimney between the hole in the chimney and the relatively larger hole in the wall is plastered to give it a finished appearance and to close the space between the chimney and the wall at 30 that point. When the wall shrinks and settles it causes the plaster on the face of the chimney to crack and often causes the plaster of the wall itself to crack due to the relative vertical movement of the two tubes 35 just described.

The object of my invention is to provide a flue receiver so constructed as to prevent such cracking of the plaster and providing means to give a neat finished appearance to 40 the face of the chimney between the two holes above described, this object being attained by providing suitable means forming a self-adjusting connection between the tube in the chimney and the tube in the wall, 45 said means permitting relative vertical movement of said tubes as the wall shrinks and settles.

Another object is to provide convenient means to close the aperture of the tube in 50 the chimney hole when there is no stove connected thereto.

The invention consists in the novel features of construction and in the combination and arrangement of parts set forth in the 55 following specification and particularly pointed out in the appended claims.

Referring to the drawing: Figure 1 is a perspective view of an adjustable flue receiver embodying my invention. Fig. 2 is an elevation viewed from the inside of the 60 wall of a house showing the adjustable flue receiver in place. Fig. 3 is a sectional view taken on line 3—3 of Fig. 2, looking toward the right.

Like numerals refer to like parts throughout the several views of the drawing.

In the drawing, 5 is a chimney extending upwardly between two walls 6 and 7 in the usual manner, said chimney being provided with a usual hole 8 for the flue and the wall 70 7 being provided with a hole 9 relatively larger than the hole 8 as is customary.

Located in the hole 8 is a tube 10 which receives a usual flue 11. Located in the hole 9 is a tube 12 with which a tube 13 is tele- 75 scopically assembled, the latter tube being preferably provided with a flange 14 resting against the face of the wall 7. I connect the tubes 8 and 12 by suitable means forming a self-adjusting connection between said tubes, 80 whereby relative vertical movement of said tubes is permitted as the wall 7 shrinks and settles. In the present instance, this means consists of a plate 15 formed on or secured to the tube 8 and resting against the face of 85 the chimney 5, said plate having formed thereon or secured thereto in any suitable manner two vertical guides 16, 16 which receive a flange 17 formed on or secured to the tube 12, thus preventing relative horizontal 90 movement of the tube 12 and the plate 15, yet permitting a vertical sliding movement of said tube and said plate. The plate 15 also forms a neat finish for the front face of 95 the chimney between the hole 8 and the hole 9.

In practice, the device is assembled with the center of the hole 9 above the center of the hole 8, as shown in the drawing, a sufficient distance so that shrinking and settling 100 of the wall 7 will bring the hole 9 into approximate co-axial location with the hole 8. Since the amount of vertical movement is different at the different floors of the building, the amount which the two tubes will be 105 offset from each other will vary at the different stories of the building and will be governed by the probable shrinking and settling of the walls. Thus it will be seen that the device automatically adjusts itself and 110 obviates the difficulties heretofore experienced.

In order that the tube 8 may be closed when there is no stove connected thereto, I provide suitable means preferably consisting of a slide 18 mounted in suitable guides 5 19, 19 on the front face of the plate 15, the tube 12 being cut away for said slide and said guides, as shown. The slide 18 is provided with suitable frictional means acting to hold the same against vertical movement, 10 such means, in this instance, consisting of a suitable spring 20 secured to the plate 15 and bearing against the back face of the slide 18.

The slide 18 is preferably provided with a 15 flange 21 adapted to engage the upper side of the periphery of the tube 12, thus limiting the downward movement of said slide and said slide is also provided with a handle 22 by which the same may be moved vertically, 20 said handle also serving as a means for limiting the upward vertical movement of said slide. When the stove is disconnected and the flue 11 removed from its place, the slide 18 is moved into position to close the aperture 25 in the tube 8.

Having thus described my invention, what I claim and desire by Letters Patent to secure is:

1. The combination with a chimney and a 30 distinct independent wall separated from each other by an air space, of an apertured plate supported upon said chimney and having its rear face disposed against the face of said chimney, a sleeve extending horizontally into said chimney, a sleeve extending horizontally into said wall from the aperture of said plate, and means located on the front face of said plate forming an adjustable connection between said sleeves and permitting 35 relative vertical movement of said chimney and said wall carrying said sleeves respectively therewith.

2. The combination with a chimney and a 45 wall, of a sleeve extending horizontally into said chimney, a sleeve extending horizontally into said wall, a plate secured to the first-mentioned sleeve, said plate being supported on said chimney and having its rear face disposed against the face of said chimney, and interengaging means on the front 50 face of said plate and the rear end of the second-mentioned sleeve permitting a relative vertical sliding movement of said sleeves.

3. The combination with a chimney and a 55 distinct independent wall separated from each other by an air space, of an apertured plate supported upon said chimney and having its rear face disposed against the face of 60 said chimney, a sleeve extending horizontally into said chimney, a sleeve extending horizontally into said wall from the aperture of said plate, means located on the front face of said plate forming an adjustable 65 connection between said sleeves and per-

mitting relative vertical movement thereof, and means located between the front face of said plate and said wall to close the opening in the first-mentioned sleeve.

4. The combination with a chimney and a 70 wall, of a plate having an aperture therein, said plate being supported upon said chimney and having its rear face disposed against said chimney, two tubes located on opposite sides, respectively, of said plate and communicating with each other through said aperture, one of said tubes being secured to said plate and extending into said chimney and the other extending into said wall, and means located between the front face of said 75 plate and said wall forming an adjustable connection between the last-mentioned tube and said plate and permitting relative movement of said tubes in a direction parallel to the plane of said plate.

5. The combination with a chimney and a 80 wall, of a plate having an aperture therein, said plate being supported upon said chimney and having its rear face disposed against said chimney, two tubes located on opposite sides, respectively, of said plate and communicating with each other through said aperture, one of said tubes being secured to said plate and extending into said chimney and the other extending into said wall, a 85 laterally extending flange on the other of said tubes, and means on the front face of said plate forming guides for said flange extending parallel to the plane of said plate.

6. The combination with a chimney and 90 a wall, of a plate having an aperture therein, two tubes of different diameters located on opposite sides, respectively, of said plate and communicating with each other through said aperture the larger of said tubes extending into said wall, the smaller of said 95 tubes being secured to said plate and extending into said chimney, and interengaging means on said plate and the larger of said tubes permitting relative movement of said plate and said larger tube in a direction parallel to the plane of said plate.

7. The combination with a chimney and a wall, of a plate having an aperture therein, two tubes of different diameters located 105 on opposite sides, respectively, of said plate and communicating with each other through said aperture the larger of said tubes extending into said wall, the smaller of said 110 tubes being secured to said plate and extending into said chimney, guides on said plate extending parallel to the plane thereof, and means on the larger of said tubes 115 engaging said guides.

8. The combination with a chimney and a 120 wall, of a plate having an aperture therein, two tubes of different diameters, located on opposite sides, respectively, of said plate and communicating with each other through said aperture the larger of said tubes ex- 125

- tending into said wall, the smaller of said tubes being secured to said plate and extending into said chimney, a third tube extending into said wall and telescopically assembled with the larger of said tubes, and interengaging means on said plate and said larger tube permitting relative movement of said plate and said larger tube in a direction parallel to the plane of said plate.
9. The combination with a chimney and a wall, of a plate having an aperture therein, two tubes of different diameters located on opposite sides, respectively, of said plate and communicating with each other through said aperture the larger of said tubes extending into said wall, the smaller of said tubes being secured to said plate and extending into said chimney, means to close said aperture, and interengaging means on said plate and the larger of said tubes permitting relative movement of said plate and said larger tube in a direction parallel to the plane of said plate.
10. The combination with a chimney and a wall, of a plate having an aperture therein, two tubes of different diameters located on opposite sides, respectively, of said plate and communicating with each other through said aperture the larger of said tubes extending into said wall, the smaller of said tubes being secured to said plate and extending into said chimney, a slide located between said wall and said chimney to close said aperture, and interengaging means on said plate and the larger of said tubes permitting relative movement of said plate and said larger tube in a direction parallel to the plane of said plate.
11. The combination with a chimney and a wall, of a plate having an aperture therein, two tubes of different diameters located on opposite sides, respectively, of said plate and communicating with each other through said aperture the larger of said tubes extending into said wall, the smaller of said tubes being secured to said plate and extending into said chimney, a slide located between said wall and said chimney to close said aperture, means on said plate to guide said slide, and interengaging means on said plate and the larger of said tubes permitting relative movement of said plate and said larger tube in a direction parallel to the plane of said plate.
12. The combination with a chimney and a wall, of a plate having an aperture therein, two tubes of different diameters located on opposite sides, respectively, of said plate and communicating with each other through said aperture the larger of said tubes extending into said wall, the smaller of said tubes being secured to said plate and extending into said chimney, a slide located between said wall and said chimney to close said aperture, means to limit the travel of said slide, and interengaging means on said plate and the larger of said tubes permitting relative movement of said plate and said larger tube in a direction parallel to the plane of said plate.

In testimony whereof I have hereunto set my hand in presence of two subscribing witnesses.

JOHN J. McDONALD.
